CLAIM

The ornamental design for a metal interconnecting member for solar cells, as shown and described.

DESCRIPTION

FIG. 1 is a top perspective view of a metal interconnecting member for solar cells showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines shown represent environment and form no part of the claimed design.
